UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

TYPEWRITER MECHANISM.

1,385,549.

Specification of Letters Patent. Patented July 26, 1921.

Application filed March 15, 1920. Serial No. 365,966.

To all whom it may concern:

Be it known that I, OTTO A. HOKANSON, a citizen of the United States, residing at Woodstock, in the county of McHenry and 5 State of Illinois, have invented certain new and useful Improvements in Typewriter Mechanism, of which the following is a specification.

This invention has for its object the provision of typewriter mechanism which shall 10 be of approved construction and operation. The invention is exemplified in the arrangement of parts shown in the accompanying drawing and described in the following 15 specification and it is more particularly pointed out in the appended claims.

In the drawing Figure 1 is a fragmentary sectional view of a portion of a typewriter illustrating one embodiment of the present 20 invention.

Fig. 2 is a vertical section on line 2—2, Fig. 1.

Fig. 3 is a fragmentary view showing a detail of construction.

25 In the drawings 10 designates a type bar segment having the usual bars 11 pivotally mounted thereon by means of a pivot rod 12 lying in a recess in the type bar segment 10. The usual platen 13 is provided to form 30 a backing against which the type strike. The type bar segment 10 is provided with a series of slots 14 in which the lower portions 35 of type bars 11 are mounted. Each bar 11 is provided with a hook 15 for engaging the pivot rod 12 and a second longer hook portion 16 for receiving a pivot pin 17 carried by a link 18 connected with the key lever mechanism in any usual and approved manner.

40 The type bar segment 10 is provided with an arcuate recess or notch 19 which follows the contour of the type bar segment and in which a universal bar 20 normally reposes. The universal bar 20 has the curved outline 45 of the type bar segment 10 so that it follows the contour of the recess 19. Each type bar 11 is provided with a projection 21 arranged to engage the universal bar 20 when the type bar is moved into printing position and 50 forces the bar 20 rearwardly or to the right as viewed in Fig. 1 of the drawing. The movement of the bar 20 under the impact of the type bar 11 is resisted by a spring, not shown, which normally holds the universal 55 bar seated in the recess 19.

The universal bar 20 is provided with a bracket 22 having a pivotal connection at 23 with an oscillating member 24 pivoted at 25 to the frame of the machine. An escapement wheel 26 is mounted on the frame 60 member 27 and controls a platen carriage rack 28 which meshes with a pinion 29 secured to the escapement wheel 26. The escapement wheel 26 is controlled by a pair of dogs, not shown, which may be of usual construction, a preferred form of said dogs being illustrated and described in my prior application, Serial No. 246,460, filed July 24, 1918. The escapement dogs are operated by a dog rocker 29 carried on a shaft 30 and 70 having one end thereof arranged to project between fingers 31 and 32 on the lower bifurcated end of the oscillating member 24. Projections 33 and 34 are provided on the dog rocker 29 for engaging the fingers 31 75 and 32 respectively on the oscillating member 24. Stops are provided for limiting the oscillatory movement of the dog rocker 29 as shown in Fig. 3. It will be apparent that when a key is struck and a type bar is operated to shift the universal bar 20 the finger 32 will move to the right as viewed in Fig. 1, and thus shift the dog rocker and the escapement mechanism. When the type bar is permitted to return to its inactive position the bracket 22 will move to the left under the influence of the spring for the universal bar and cause the finger 31 to engage the projection 33 and again shift the dog rocker to complete the operation of the 80 escapement mechanism.

85 Under normal conditions it is desirable that the type bars shall be retained in their pivotal relation with the type bar segment and this is effected by the universal bar 20 90 which bears upon all of the type bars and prevents their disconnection from the pivot rod 12. Normally the universal bar 20 cannot be moved to the right in Fig. 1 a sufficient distance to permit disconnection of 100 the hook 15 from the pivot rod 12. It is sometimes desirable however to remove a particular type bar for repairs or for replacement or other reasons and provision is made to permit such removal when it becomes desirable. Stamping 35 is pivoted at 105 36 to a lug 37 formed on the oscillating member 24. This stamping 36 is provided with a tailpiece 38 which lies between the finger 32 and the projection 34 on the dog 110

rocker 29. A coil spring 39 is secured to the end of the tailpiece 38 and to an eye 40 on the oscillatory member 24 and normally holds the tailpiece in position adjacent the finger 32. A stop shoulder 41 is formed on the tail-piece 38 to limit the movement of the stamping 35 under the influence of the spring 39. Under ordinary operation the finger 32 operates through the tail-piece 38 to move the dog rocker 29. The stamping 35 is provided with a finger piece 42 by which the stamping may be moved about its pivot 36 against the tension of the spring 39 to withdraw the tail-piece 38 from between the finger 32 and the projection 34. When the tail-piece is thus removed the bracket 22 and the universal bar 20 may be moved to the right, as viewed in Fig. 1, a distance beyond the normal limit of its movement, an amount equal to the thickness of the tail-piece 38. This extra movement of the universal bar 20 is sufficient to permit the hook 15 to move to the right as viewed in Fig. 1 until it becomes disengaged from the pivot bar 12. The lower end of the type bar 11 is usually so shaped that it is necessary to swing the bar downwardly away from the platen before it can be unhooked from the pivot rod 12. It will be noted that the type bar segment 10 at the upper end of the wheel 14 is provided with an overhanging ledge 43 for preventing foreign material from accumulating in the slot 14 and this overhanging ledge would prevent disconnection of the type bar from the pivot 12 when the type bar is in its printing position where the bars are shaped as shown in the figure of the drawing. When the hook 15 has been disengaged from the pivot rod 12 the type bar will be free to slide downwardly and forwardly to disengage the hook 16 from the pivot 17 of the key lever mechanism 18 and in this way the type bar may be entirely disconnected from the machine.

45 I claim:

1. In a typewriter having escapement mechanism, a dog actuating device for controlling said mechanism, an oscillatory member for operating said dog actuating de-

vice, said oscillatory member having fingers for engaging said actuating device; and a stop movable into and out of position between one of said fingers and said dog actuating device.

2. The combination with a typewriter having escapement mechanism; of a dog actuating device for controlling said escapement mechanism; a bifurcated oscillatory member positioned to stride said actuating device; a universal bar for moving said bifurcated member; a stop positioned between said dog actuating device and one branch of said bifurcated member for transmitting movement from said bifurcated member to said dog actuating device, said stop being movable out of position to permit excess movement of said bifurcated member and resilient means for retaining said stop in position.

3. In a typewriter, a type bar segment, a type bar having an open hook thereon for pivotally mounting said bar on said segment, a universal bar for retaining said hook in position on its pivotal support, escapement mechanism for said typewriter, a dog-actuating member for controlling said escapement mechanism, an oscillatory member having spaced abutments for engaging opposite sides of said dog-actuating member, means for connecting said oscillatory member with said universal bar for moving said oscillatory member when said type bar is operated, a stop pivotally connected with said oscillatory member to swing into and out of position between said abutments to vary the amount of opening therebetween, and resilient means for holding said stop in position between said abutments to transmit movement from said oscillatory member to said dog-actuating member and to limit the movement of said universal bar to retain said type bar in position on its pivotal mounting.

In testimony whereof I have signed my name to this specification on this 9th day of March, A. D. 1920.

OTTO A. HOKANSON.
